UNITED STATES PATENT OFFICE.

JOHN M. HARTMAN, OF PHILADELPHIA, PENNSYLVANIA.

BLAST-FURNACE.

SPECIFICATION forming part of Letters Patent No. 244,454, dated July 19, 1881.

Application filed October 21, 1880. (No model.)

To all whom it may concern:

Be it known that I, JOHN M. HARTMAN, a citizen of Philadelphia, State of Pennsylvania, have invented new and useful Improvements in Blast-Furnaces for Metallurgical Purposes, 5 of which the following is a specification.

The object of this invention is to increase the duration and facilitate the operations of the furnace.

10 The invention consists, first, in a new form of removable bosh for blast-furnaces; second, in improvements in the cinder-discharge; third, in improvements in the iron-discharge. I attain these objects by the means illustrated 15 in the following drawing, in which the figure shows a vertical section of the furnace with the new arrangement of bosh or slope, the cinder-discharge and the iron-discharge.

Blast-furnace linings as heretofore built consist of two parts: first, the upper lining or inner walls, extending from the widest part of the interior of the furnace to the top of the furnace; second, the crucible or hearth and the bosh or slope, extending from the bottom of 25 the furnace to the widest part of the interior of the furnace. This slope or bosh is soon worn away by the attrition of the descending coal, ore, and stone, and requires frequent renewals. The slope and crucible walls being built in one 30 mass or body, it becomes necessary to tear out the walls forming both the slope and crucible walls when the slope is to be rebuilt. To obviate this I build the crucible-walls thin to prevent their burning away, and carry them 35 up above the fusion limit. I then build the slope or bosh *a*, Figure 1, separate from the upper walls, *b*, and separate from the crucible-walls *c*. This admits of the renewal of the bosh or slope without destroying the other 40 walls. I do not broadly claim a bosh or slope.

In discharging the cinder from a blast-furnace through the form of cinder-notch usually employed the inner walls of the crucible around the notch are rapidly destroyed by the cinder, 45 which is intensely hot. The *U*-shape box heretofore used to hold the cinder-notch is of such a shape that the coil or pipe cast in it cannot be wound close together. The hot cinder melts the cast-iron from the coil and soon 50 burns off the coil, as it is not wound close enough to give sufficient cooling-surface to chill

the cinder and hold it in check. By making a circular water-breast, *v*, Fig. 1, to hold the notch, the coil can be wound close, giving a continuous cooling-surface the whole length of 55 the breast.

When a furnace works irregularly some of the iron is discharged through the cinder-notch. This destroys the coil in the breast holding the notch and compels its renewal. 60

By making the breast in two sections, *v* *s*, one part to slip in the other, a small part of the breast only has to be renewed. The space between the larger and smaller breast is packed 65 with clay.

By placing a dam, as at *t*, across the larger end of the smaller breast part of the cinder is held back. This cinder forms a covering on the bottom of the breast, which protects the 70 coil from the flowing iron.

By increasing the cooling-surface in a given space, as described, the melting of the walls surrounding the breasts is avoided, and the furnace is thereby kept longer in blast. 75

In operating the furnace there are times when the heat in the hearth becomes so low 80 that the cinder will not flow through the small opening of the notch. It then becomes necessary to get a large opening into the furnace for blowing out the partly-fused material in the furnace, and thereby to get fresh coal down to the tuyeres. By taking out the inner breast, *v*, a large opening is got into the furnace at once. The combustion of the fresh coal arriving at the tuyeres increases the heat quickly, 85 causes the cinder to flow rapidly, and separates the iron from the cinder. The coil can be omitted in these circular breasts, and an annular water-space be used in place of the coil. 90

I do not claim the controlling of the flow of slag through a water-cooled discharge-piece or cinder-block; nor do I claim the cinder-block *u* shown in breast *T*.

To discharge the molten iron from the bottom of a blast-furnace a hole is left in the bottom of the water-jacket surrounding the furnace. The rapid flow of the iron soon cuts away the sides of the opening and makes it so large that difficulty is experienced to stop the 95 hole after casting and to prevent the iron breaking out before next casting. To obviate this 100

water-coils have been cast in the jacket to preserve it; but at times the flow of the iron is so rapid that the water in the coil becomes hot, forms steam, and the coil is burned off. When 5 the coil burns off the water is forced through the molten iron, causing terrific explosions, which burn the workmen and often destroy their lives.

When the iron flows too rapidly from the 10 furnace the pig-beds are overflowed, forming scrap-iron in place of good marketable iron.

By inserting in the tapping-hole a hollow 15 plug, V, having a circulation of cold air through it, the flow of the iron can be controlled, and in event of a plug being destroyed the air will cause no explosion.

The pipe x to supply the cold air can be attached direct to the main cold-blast pipe of the 20 furnace.

I claim no material between the flow of the molten metal and the hollow plug V.

I disclaim any regulation of the flow of cin-

der by causing more or less water to flow through the circular water-breasts in claim 2.

I do not broadly claim a bosh situated above 25 the fusion limit, as this was granted me in Patent No. 228,528, June 8, 1880.

I disclaim a removable bosh situated wholly or partly below the fusion limit.

I claim—

1. A blast-furnace provided with a separate and detachable bosh or slope situated above the fusion limit, substantially as described.

2. In connection with the cinder-discharge of a blast-furnace, the internal and external 35 water-breasts, *s v*, substantially as herein described.

3. The combination, in a blast-furnace, of a hollow tap-hole casing or plug and a pipe for supplying said casing with air.

JOHN M. HARTMAN.
